UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT BREAKER.

Application filed January 3, 1923. Serial No. 611,260.

My invention relates to a system of installation for circuit interrupters in power stations, more particularly to a system in which circuit interrupters for a polyphase circuit are arranged in vertical alinement.

One object of my invention is to provide an installation for circuit interrupters in connection with polyphase electrical circuits in which a circuit interrupter is placed in each phase of the circuit and the several associated circuit interrupters are placed in vertical alinement.

Another object of my invention is to provide a common controlling means for tank lifters used in connection with a plurality of circuit interrupters placed in alinement.

It is also an object of my invention to provide an arrangement of circuit interrupters and actuating means therefor, which require a minimum of floor space at the expense of the vertical space.

It is a further object of my invention to provide, in an installation of circuit interrupters in vertical alinement and having a common means for controlling movement therefor, means for preventing the operation of the controlling mechanism until the several interrupters have been placed in their correct operating positions.

Still another object of my invention is to provide means for preventing the accidental movement of any one of a plurality of interconnected circuit interrupters until all of the interrupters are in their proper position for such movement.

In my co-pending application Serial No. 611,258, filed Jan. 8, 1923, I have shown and described an arrangement of circuit interrupters in which it is necessary to employ a large amount of shafting and in which it is necessary to have a tank lifter for each circuit interrupter. In the present invention, I propose to eliminate a large portion of the shafting and to provide a single interchangeable tank lifter for each floor of the power station, thereby materially reducing the amount of apparatus required in such a power station without reducing the advantages gained by the installation as a whole.

In the accompanying drawing,

Figure 1 is a sectional view of the several floors of a power station and a side elevation of circuit interrupters and lifters embodying my invention.

Fig. 2 is a face view of a wall of a power station embodying my invention.

Fig. 3 is an enlarged sectional view of a single floor of a power station showing the details of my invention.

In the preferred embodiment of my invention, a power station 1 having a plurality of floors or levels 2, 3, 4 and 5, certain of which support circuit interrupters 6, is equipped with portable tank lifters 7 for the simultaneous removal and disconnection of a plurality of circuit interrupters from an electrical circuit. The tank lifters are provided with common connecting means comprising a shaft 8, and gear mechanisms 9. A motor 10, which is placed on the upper floor 2 in vertical alinement with the series of circuit interrupters 6 to be actuated, is operatively connected to the shaft 8 by means of bevel gear mechanism 11.

This invention is applicable to any type of circuit interrupter which consists of a tank 12, a cover 13 and suitable cover-retaining means. However, I prefer to employ the retaining means 14 illustrated herein and shown and described in my co-pending application, Serial No. 604,492, filed Dec. 2, 1922. The disconnecting mechanism 14 is permanently attached to beams 15 forming a part of the permanent structure of the power station 1. The tank 12 is provided with ears 16 which cooperate with levers 17, the latter forming part of the securing means 14.

A secondary partition 18 projects from the wall of the station 1 intermediate the floors 2, 3, 4 and 5. These partitions support bushings 19 which form the fixed terminals for electric conductors 21. The contact members for each conductor 21 consist of a spring 22 and a movable member 23, the latter being a part of the circuit interrupter, whereby a disconnecting switch is obtained.

The lower faces of beams 15 are equipped with flanges 24 which co-operate with flanges 25 mounted on the tank 12 and flanges 25a attached to the cover members 13, for purposes to be hereinafter described. The flanges 25a are of greater diameter than the flanges 25.

A portable tank lifter 7 of any suitable construction, is placed on each floor of the power station, as is shown in Figure 2. Such a tank lifter consists of a bed 20 and supporting frame 26, wheels 27, adjustable arms 28, ver-

tical adjusting screws 29 for the movable arms 28, a shaft 31 mounted beneath the bed 20, an extension 32 formed on shaft 31 and a bevel gear connection 33 between shafts 29 and 31. The extension 32 preferably carries a gear 34 adapted to pass through an opening in the wall and in the support 35 secured to the station wall.

The gear connection 9 comprises support 10 35 having arms 36 and 37 in which is journaled a short shaft 38. A gear wheel 39 is mounted on the shaft 38 between the arms 36 and 37, and has a geared connection to shaft 8. A collar is secured to shaft 38 immediately below the arm 37. This collar is provided with a notch 42 and a bevel gear face 43. A latch member 44 is pivotally supported, as at 45, on the arm 37 and is adapted to engage the notch 42 by force of gravity.

20 In practice it has been found advisable to place the circuit interrupters for the several polyphase circuits in vertical alinement thereby eliminating any cross-connecting mechanism, such as is essential to a horizontal disposition of circuit interrupters for a polyphase system, as is the customary practice.

In the operation of my invention, the 30 latches 44 normally fit into the notches 42 in collars 41, as is shown by the dotted line position of member 44 in Fig. 3. Because of the interconnection between the latch 44 and the notch 42, rotation of the shafts 8 and 38 is normally prevented. If any circuit 35 interrupter 6 is to be repaired the lifter 7 on that floor is placed under the flange 25 and between the beams 15. Movement of the lifter 9 into position causes the extension 32 and gear members 34 to pass through the wall and support 35, the gears 34 and 43 making contact, and extension 32 making contact with the latch 44 lifting the latter clear of the notch 42.

40 When this has been done on the several floors of the station, and not until then, the shaft 8 is free to rotate. The shaft 8 is then actuated by the motor 10 and motion is imparted to the support 29 through shaft 31 and gear 32. By controlling the direction of rotation of the motor 10, members 29 are caused to rotate in such direction that the arms 28 move upwardly or downwardly as desired.

55 In the process of opening a circuit interrupter the detachable mechanism 14 is loosened as soon as the lifter 7 is in position. As has been previously stated the levers 17 of the mechanism 14 are pivotally secured to the beams 15. As soon as the levers 17 have 60 been loosened sufficiently to clear the extensions 16 of the tank member 12, the weight of the tanks 12 and the cover 13 is shifted to the arms 28. Rotation of the motor 10 then causes the arms 28 to move downwardly carrying with them the entire circuit interrupt-

ter structure, including contact members 23, thereby causing a disconnection between contact members 22 and 23. By this operation it is assured that all parts of a circuit interrupter 6 are electrically disconnected. 70

Downward movement of the arms 28 is continued until the flanges 25a of the cover members 13 bear against the flanges 24. Further downward movement of the cover portion 13 is prevented because of the contact 75 between the flanges 24 and 25a.

Further downward movement of the arms 28 permits the flanges 25 on the tank portions 12 to pass between the flanges 24 until the tanks 12 rest upon the beds 20 of the several 80 lifters 7.

The motor 10 is then stopped. The lifters 7 are withdrawn from between the beams 15 and the tanks are taken to any suitable place for such repairs as may be needed. The cover 85 members 12 are then accessible for such repairs as may be found necessary. The withdrawal of extensions 32 from the supports 35 permit the latches 44 to fall into the notches 42 thereby preventing rotation of the shaft 8. 90

In order to replace a circuit interrupter, the reverse process is used. The tanks being placed in position and supported by the several beds 20 and supports 28. When all the tanks are in place the opposite rotation is 95 given to the shaft 8 causing the tanks to be raised until contact is made between cover members 13 resting on the flanges 24. Upward movement is then continued until contact members 22 and 23 are brought into contact when extensions 16 are connected with the levers 17. The supports 28 are then freed from the flanges 25 and the lifters 7 are withdrawn. 100

By this invention I have provided means 105 for simultaneously opening and removing the circuit interrupters for all phases of a polyphase electric circuit. I also employ a small number of moving parts with a minimum of floor space. 110

My invention is not limited to the specific structure illustrated, as it may be variously modified without departing from the spirit and scope of the invention, as set forth in the appended claims. 115

I claim as my invention:

1. In a circuit interrupting system for a polyphase circuit, a circuit interrupter for each phase of said electrical circuit, a portable lifter for each of said circuit interrupters 120 and means common to all the circuit interrupters of each electrical circuit for operating said lifters and means for operating the first mentioned operating means.

2. In a circuit interrupting system for a polyphase circuit, a circuit interrupter for each phase of said electrical circuit, a portable lifter for each of said circuit interrupters, means common to all the circuit interrupters for operating said lifters, and 130

means associated with the first named operating means for preventing its operation until the lifters for all the circuit interrupters of the electrical circuit are in place.

5 3. In an electrical apparatus, a plurality of circuit interrupters one on each of a plurality of levels, a portable lifter on each level adapted to operatively engage said circuit interrupter thereon and means common to a plurality of levels for simultaneously operating a plurality of said lifters to raise or lower the circuit interrupters engaged thereby.

10 4. In an electrical apparatus, a plurality of circuit interrupters, a portable lifter for each of said circuit interrupters, means common to a plurality of said circuit interrupters for simultaneously operating the associated lifters, and means for preventing the 15 operation of said common operating means while any one of said lifters is out of its operative position.

20 5. In an electrical device, a plurality of circuit interrupters in vertically aligned relation, a portable lifter for each of said circuit interrupters, and means common to all of said circuit interrupters for simultaneously operating said lifters.

25 6. In an electrical device, a plurality of circuit interrupters in vertically aligned relation, a portable lifter for each of said circuit interrupters, means common to all of said circuit interrupters for simultaneously operating said lifters, and a motor in vertical relation 30 to said circuit interrupters for operating said common operating means.

35 7. In an electrical device, a plurality of circuit interrupters in vertically aligned relation, a portable lifter for each of said circuit interrupters, and means common to all of said circuit interrupters for simultaneously operating said lifters, a motor in vertical relation to said circuit interrupters for operating said common operating means, and means for 40 preventing the operation of said common operating means until all of said lifters are in their operating positions.

45 8. In an electrical device, a plurality of circuit interrupters in vertically aligned relation, a portable lifter for each of said circuit interrupters, and a shaft common to all of said circuit interrupters for simultaneously operating said lifters.

9. In an electrical device, a plurality of circuit interrupters in vertically aligned relation, 55 a portable lifter for each of said circuit interrupters, a shaft common to all of said circuit interrupters for simultaneously operating said lifters, and a motor in vertical relation to said circuit interrupters for operating said shaft.

10. In an electrical device, a plurality of circuit interrupters in vertically aligned relation, a portable lifter for each of said circuit interrupters, a shaft common to all of said 60 circuit interrupters for simultaneously operating said lifters, a motor in vertical relation to said circuit interrupters for operating said shaft, and latching means for preventing the operation of said shaft until all of said lifters 65 are in their operating positions.

11. In combination, a shaft, a support for said shaft, a latch carried by said support, a disk provided with a notch secured to said shaft for engagement with said latch, a second shaft, a bevel gear connection between said shafts, said second named shaft having a detachable connection with said bevel gear, an extension formed on said second named shaft adapted to lift said latch from said 70 notch when said second shaft is in operative engagement with said bevel gear.

12. In combination, a tank lifter, a shaft, a support for said shaft, a latch carried by said support, a disk provided with a notch secured to said shaft for engagement with said latch, a second shaft carried by said tank lifter, a bevel gear connection between said shafts, said second named shaft having a detachable connection with said bevel gear comprising an extension adapted to lift said latch 80 from said notch when said tank lifter is in its operative position.

13. In an electrical system, a plurality of circuit interrupters at each of a plurality of levels, a portable lifter at each of said levels, one of said circuit interrupters at each of the levels being adapted for connection to one phase of a polyphase electrical circuit, and means for simultaneously operating the lifters co-operating with the several circuit interrupters of the electrical circuit.

In testimony whereof, I have hereunto subscribed my name this 8th day of December, 1922.

CHRISTIAN AALBORG.
